DRY HAND MOP

Filed June 2, 1927

UNITED STATES PATENT OFFICE.

DONALD McDONALD, OF DAVENPORT, IOWA.

DRY HAND MOP.

Application filed June 2, 1927. Serial No. 195,992.

My invention relates to improvements in dry hand mops.

The objects of my invention are:

1. To provide a mop in which a single strand with a plurality of bights formed therein is used for the fabric;
2. To provide a method of securing the fabric to the lower end of the mop stick in such a way that the mop stick cannot mar 10 the floor;
3. To provide an enlarged head of fabric at the lower end of the mop stick;
4. To provide a superior means of securing the fabric to the sliding handle;
5. To provide a mop of superior efficiency 15 which can be simply manufactured and produced in quantity.

I attain these objects by the means illustrated in the accompanying drawings, in 20 which,—

Figure 1 is a full length view of the top with the handle end of the mop stick down; Fig. 2 is an enlarged longitudinal detail of the opposite end of the mop stick; Fig. 3 is an 25 enlarged sectional detail of the sliding handle showing the method of securing the fabric thereto; Fig. 4 is an enlarged longitudinal sectional detail of the end of the mop; Fig. 5 is a sectional detail showing the method 30 of applying the fastening wires to the end of the mop and Figure 6 is a sectional detail showing the method of fastening the fabric in the groove near the end of the mop.

The mop comprises a mop stick, 1, which is 35 the ordinary round rod of wood having the end to which the fabric is attached reduced as shown at 4 in Figure 2 and with an annular groove, 3, cut in the mop stick near the end thereof. A hole, 5, is bored through the 40 body of the mop stick within the groove, 3, and extends clear through the stick.

A sliding handle, 2, comprised of wood with a central bore, is mounted upon the mop stick, 1, and preferably has a pair of annular 45 grooves, 6 and 7, formed therein.

The fabric of the mop is composed of a continuous strand of heavy yarn or cord of cotton or other suitable material, with a plurality of loops or bights formed at each 50 end of the fabric. A wire, 9, is passed through the loops at one end of the fabric and secures them in the groove, 7. A wire, 8, which may be applied in either a single or double turn, binds the fabric in the groove, 55 6, of the handle, 2. These wires are secured

by twisting them together and bending the ends down in the ordinary way.

The opposite end of the fabric is secured to the end of the mop stick by a wire, 11, which passes through the loops or bights of the cord of which the fabric is composed and binds them closely to the reduced end, 4, of the mop stick, 1.

An additional wire, 10, binds the fabric in the groove, 3, near the end of the mop stick. The wire, 10, is preferably applied as shown in Figures 5 and 6, the loose ends of the wire being passed through the hole or bore, 5, leaving two strands of the fabric, 12^a, within the loop and two strands of the fabric, 12^b, between the wires, 10, as they leave the hole or bore, 5.

The loop is then bent over the end of the mop stick and the wires drawn up tight, one of the wires passing through the loop and the other one outside of it. The wires are then crossed over the two strands, 12^b, and wrapped in opposite directions around the mop stick and fabric and the ends are then twisted together as at 10^a in Figure 6.

In Figure 6, for clearness of illustration, I have shown the wire, 10, before it is finally tightened and in Figure 5 I have omitted the fabric excepting only the strands, 12^a and 12^b. In constructing my mop in this way, the ends of the bights or loops project sufficiently beyond the end of the mop stick to prevent the mop stick scratching or rubbing upon the floor, while the double wiring secures it firmly to the end of the mop stick and the wires passing through the bore, 5, absolutely prevent the lower end of the fabric turning upon the mop stick when the mop is being wrung in the ordinary way.

In securing the fabric to the end of the 95 mop stick as described, the gathered ends of the loops around the reduced end of the mop stick form a pretty good-sized head or ball, much larger than appears in Figure 4, and forms a very desirable feature as this head 100 can be used to scrub a particularly dirty spot with good effect and without danger of marring the floor.

It should also be noted that my method of 105 securing the fabric to the sliding handle forms a firm attachment therefor and the protruding portions of the fabric protect the hand of the operator from contact with the wires.

In the drawings, the size of the strand com- 110

posing the fabric is much smaller than that in actual use. In actual use, I prefer to use a four-strand yarn or cord of approximately one-fourth of an inch in normal diameter.

5 It is obvious that this mop could be wrung out by turning the mop stick, 1, relatively to the handle, 2; or by holding the mop stick, 1, stationary, and turning the handle, 2, upon it. A grip, 13, preferably formed of an 10 octagonal block of wood bored out to fit the handle and nailed or otherwise secured to it, aids in giving the operator a firm grip upon the handle in wringing out the mop.

I claim:

15 1. A mop fastening comprising a mop stick having a transverse bore at its lower end, a stranded mop fabric secured thereon, a doubled wire passing through the bore and embracing a number of the strands within a 20 loop formed by the doubling of the wire, this

loop being then re-bent so as to surround the lower end of the mop stick, the free ends of the wire being then drawn taut and re-bent upon and around the mop stick and fabric, and united.

2. A mop fastening comprising a mop stick having a transverse bore at its lower end, a stranded mop fabric secured thereon, a doubled wire passing through the bore and embracing a number of the strands within a 30 loop formed by the doubling of the wire, this loop being then re-bent so as to surround the lower end of the mop stick, the free ends of the wire, one being above and the other below the looped portion, being then drawn taut and re-bent upon and around the mop stick and fabric, and united.

In testimony whereof he affixes his signature.

DONALD McDONALD.
